UNITED STATES PATENT OFFICE.

JOSEPH MAAS, OF KALAMAZOO, MICHIGAN.

DESIGN FOR A GAS-LAMP.

No. 38,699.

Specification for Design.

Patented July 23, 1907.

Application filed February 11, 1907. Serial No. 356,938. Term of patent 14 years.

To all whom it may concern:

Be it known that I, JOSEPH MAAS, a citizen of the United States, residing at Kalamazoo, in the county of Kalamazoo and State of Michigan, have invented a new, original, and ornamental Design for Gas-Lamps, of which the following is a specification, reference being had to the accompanying drawings, forming a part thereof.

The drawing is a perspective view of a gas lamp showing my new design.

I claim:

The ornamental design for gas lamp, as shown.

JOSEPH MAAS.
